CLAIM

I claim the ornamental design for a motorcycle radio mounting box, as shown and described.

DESCRIPTION

FIG. 1 is a front perspective view of a motorcycle radio mounting box as according to the claimed invention;

FIG. 2 is a front side view of the motorcycle radio mounting box of FIG. 1;

FIG. 3 is a back side view of the motorcycle radio mounting box of FIG. 1;

FIG. 4 is a top side view of the motorcycle radio mounting box of FIG. 1; and,

FIG. 5 is a left side view of the motorcycle radio mounting box of FIG. 1.

The broken lines immediately adjacent the shaded areas represent the boundaries of the claimed design while all other broken lines are directed to environment and are for illustrative purposes only; the broken lines form no part of the claimed design.
